SIGHT FOR TRENCH EXCAVATORS

Daniel F. Przybylski, Winona, Minn.

Application March 28, 1949, Serial No. 83,916

1 Claim. (Cl. 33—185)

1
My present invention relates to improvements in sights and, more particularly, to a sight for use in connection with a trench excavator.

While this invention is intended for general use in connection with machines that operate to an established grade, it is especially designed for use in connection with my improved trench excavator disclosed and broadly claimed in my pending United States application filed September 7, 1948, under Serial Number 48,121.

The object of this invention is to permit the operator of a trench excavator to keep the boom of said excavator, which carries the shovels that travel an endless course, in a position in which the shovels dig to an established grade for the bottom of the trench being dug according to stakes set by a surveyor.

To the above end, the invention consists of the novel devices and combination of devices herein-after described and defined in the claim.

In the accompanying drawings, which illustrate the invention, like characters indicate like parts throughout the several views.

Referring to the drawings:

Fig. 1 is a side elevational view of a trench excavator of the full track type having the invention embodied therein and also showing two grade stakes;

Fig. 2 is a fragmentary detail view of one of the grade stakes, on an enlarged scale, and looking at the same from the line 2—2 of Fig. 1;

Fig. 3 is a side elevational view of the improved sight and a fragment of the boom structure to which the sight is secured, on an enlarged scale, some parts of the sight being broken away and other parts sectioned;

Fig. 4 is a front end view of the sight frame, as shown in Fig. 3;

Fig. 5 is a fragmentary plan view of the sight frame, as shown in Fig. 3;

Fig. 6 is a view principally in elevation, with some parts sectioned on the line 6—6 of Fig. 1, and with other parts shown in a different position by means of broken lines, on the same scale as Fig. 3; and

Fig. 7 is a fragmentary view partly in elevation and partly in section on a greatly enlarged scale.

For the purpose of showing the improved sight in working position, there is shown in Fig. 1 a trench excavator of the full track type shown in the application heretofore referred to. This trench excavator is indicated as an entirety by the numeral 8, with the exception of the boom 9, the shovels 10 carried by a driven endless chain 11 on said boom, the upstanding frame 12 and the

5 seat 13 for an operator x for the trench excavator. The seat 13 is located at one side of the trench excavator 8 so that the operator x has a clear vision rearward of said excavator and the work being performed thereby.

10 The improved sight is carried by the boom 9 and has a skeleton frame that includes a pair of laterally spaced side sections 14, each in the form of a right-angled triangle. One of the right-angle members 15 of each side section 14 is relatively short and vertically disposed, while the other right-angle member 16 is relatively long and horizontally disposed. The oblique member 17 of each side section 14 which is the hypotenuse of the triangle, is under the member 16.

15 The apexes of the side sections 14 point rearwardly relative to the trench excavator 8 and the side sections 14 are secured to the frame 12 at the lower end portions of the vertically disposed members 15, as indicated at 18. Each side section 14 is further secured to the frame 12 by a flat brace bar 19. The top members 16 of the two side sections 14 are rigidly connected by front, rear and intermediate cross-tie channel bars 20, 21, and 22, respectively, and positioned with their flanges horizontally disposed. The members 15, 16 and 17 of the side sections 14 are angle bars and the members 16 and 17 of each side section 14 are intermediately connected by upright angle bars 23. The members 15 and the front channel bar 21 are rigidly connected by webs 24.

20 The sight 25 is suspended from the rear channel bar 21 and includes a pendulum bar 26 attached, at its upper end, to said channel bar by a coupling 27 for compound swinging movement longitudinally and transversely of the trench excavator 8. This coupling 27 includes a head 28 rigidly secured to the pendulum bar 26, at its upper end portion, and has a pair of upstanding ears 29 laterally spaced transversely of the trench excavator 8. A short link 30 extends between the ears 29 and is pivoted thereto. This link 30 also extends between a pair of depending ears 31 on the lower flange of the channel bar 21 and pivoted thereto for swinging movement transversely of the trench excavator 8. On the lower end of the pendulum bar 26 is a pendulum weight 32.

25 An assembly mount, in the form of a long horizontal tubular bar 33, is rigidly secured, at its longitudinal center, to the pendulum bar 26 near its upper end and extends transversely of the trench excavator. A mount 34 for a tubular sight bar 35 is mounted on the end section of the

tubular bar 33 that projects from the said side of the trench excavator on which the seat 13 is located. This mount 34 includes a sleeve 36 slidably mounted on the bar 33 and secured where adjusted thereon by a hand screw 37 having threaded engagement with the sleeve 36 and impinging the bar 33. The hand screw 37 is provided with a lock nut 38. The mount 34 further includes a vertical sleeve 39 in which the sight bar 35 is slidably mounted and is held where adjusted in said sleeve by a hand screw 40 having threaded engagement with said sleeve and impinging the sight bar 35. This hand screw 40 is provided with a lock nut 41. The sight bar 35 is provided at one end with a T-head 42. The sight bar 35 is mounted in the sleeve 39 for endwise reversal so as to position the T-head 42 above the bar 33, as shown by full lines in Fig. 6, or below said bar, as shown by broken lines. A balancing weight 43 is slidably mounted on the opposite end portion of the bar 33 from the mount 34.

Rearwardly of the trench excavator 8 are two grade stakes 45, each having a T-head 46 with which the T-head 42 of the sight is aligned. The T-head 42 on the sight 25 is kept aligned with the T-heads 46 on the grade stake by raising or lowering the boom 9 to control the depth at which a trench is dug by the shovels 10.

The drawings illustrate a commercial form of the invention, but it will be understood that the same is capable of certain modifications as to details of construction, arrangement and combina-

tion of parts within the scope of the invention herein disclosed.

What I claim is:

5 A pair of laterally spaced side frames applicable in fixed positions to the sides of the shovel carrying boom of a trench excavator, each side frame being formed of bars in right-angle triangle arrangement, one bar of the right-angle being upright and the other bar thereof extending rearwardly from the top of the upright bar, a cross-tie bar connecting the two side frames at their outer ends above the boom, a pendulum attached to the cross-tie bar at the intermediate portion for swinging movement both longitudinally and transversely of the boom, and a sight including a horizontal member above and outwardly of one of the side frames and mounted on the pendulum for adjustment both vertical and horizontal.

DANIEL F. PRZYBYLSKI.
